UNITED STATES PATENT OFFICE

2,458,387

MACHINE FOR COMPACTING MATERIAL
IN CONTAINERSHarold V. Kindseth, Minneapolis, Minn., assignor
to Bemis Bro. Bag Company, Minneapolis,
Minn., a corporation of Missouri

Application January 26, 1946, Serial No. 643,573

2 Claims. (Cl. 259—72)

1

This invention relates to new and useful improvements in machines or apparatus for settling and compacting material, such as flour and other finely ground or pulverized materials, in flexible walled containers, bags, and the like, prior to closing and sealing the open tops of the containers.

An object of the present invention is to provide, in combination with a bag shaker or vibrating means of the general class disclosed in the patents to D. Belcher et al., 1,995,271 and 2,234,953, means mounted for traveling movement with the bags adapted to intermittently engage and indent opposite sides of the bag bodies, as the bags travel through the machine, thereby to cause the contents of the bag bodies to become more firmly settled therein.

A further object is to provide a machine for compacting the contents of a bag body, comprising a conveyor belt for advancing the bags through the machine, and side belts being provided adjacent to the conveyor belt having vertically disposed cleats thereon, and means being provided in conjunction with the side belts for imparting a patting action thereto, whereby the cleats on the side belts will indent the walls of the bag bodies to successively displace portions of the material in the bags, the patting action imparted to the bag bodies by the side belts cooperating with the vibratory action imparted to the bag bodies by the conveyor belt to cause the contents of the bags to quickly become firmly settled therein, whereby as the bags are discharged from the machine, the open tops thereof may be closed and sealed with the assurance that the walls of the sealed bag bodies will retain their shapes and will not be likely to become loose and shapeless, as when the material is not firmly compacted in the bag bodies before the tops thereof are sealed.

A further and more specific object of the invention resides in the combination with a conveyor belt having means for imparting a vibratory action thereto to shake the filled bags in rapid succession, comprising opposed side belts mounted for traveling movement with the conveyor belt, and each side thereof having a plurality of vertically disposed cleats secured thereto in spaced relation lengthwise of the belt, and a backing plate or member being provided for each side belt having means for imparting a horizontal motion thereto in opposed relation to one another, which horizontal motion is sufficient to cause said plate members to intermittently move into and out of contact with the side belts to

2

thereby impart a patting action thereto, which, in turn, is transmitted to opposite walls of the bag bodies by the side belts, the cleats carried by said side belts indenting the walls of the bag bodies along vertical areas, whereby they are constantly displacing portions of the contents of the bag bodies to cause the material to become more firmly settled therein as the bags are vibrated by the conveyor belt, said cleats also functioning to keep the bags in upright positions as they travel through the machine, and whereby should one of the bags be slightly canted in a forward or rearward direction, such canted bag will immediately be straightened or squared with the conveyor so that the axes of the bag bodies will be disposed in substantially right angles to the horizontal conveyor belt.

Other objects of the invention reside in the arrangement of the cleated side belts with respect to the horizontal conveyor belt, whereby the side belts continuously impart a patting action to the bag bodies as they advance through the machine, which action, in combination with the vibratory action imparted to the bag bodies, will cause the contents of the bag bodies to become firmly settled therein in a comparatively short space of time, whereby the overall length of the machine may be reduced to a minimum to conserve floor space; in the arrangement and construction of the side belts whereby they act to square or align the bags on the conveyor; and in the provision of such an apparatus which is extremely simple and inexpensive in construction, and wherein all of the parts are readily accessible, whereby the apparatus lends itself for manufacture at minimum cost.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the drawings:

50 Figure 1 is a longitudinal sectional view through the upper portion of the machine showing the relationship between the horizontal conveyor belt and the cleated side belts;

Figure 2 is a plan view of Figure 1, showing the 55 side belts in their innermost positions whereby

the cleats thereof indent the bag walls to displace portions of the contents of the bags;

Figure 3 is an enlarged detail view showing the side belt backing plates or members in their outermost positions, whereby they are spaced from their respective side belts in position to impart a patting action thereto;

Figure 4 is an enlarged detail sectional view of a portion of one of the side belts showing one way of forming the cleats thereon;

Figure 5 is a cross-sectional view on the line 5-5 of Figures 1 and 2, on a larger scale, and with some of the parts omitted, showing the driving means for the side belt backing plates or members;

Figure 6 is a cross-sectional view on the lines 6-6 of Figures 1 and 2, on a larger scale, showing the driving means for the side belts; and

Figure 7 is a diagrammatic view illustrating the horizontal movement imparted to the backing plates to cause them to impart a patting action to the side belts.

In the selected embodiment of the invention herein disclosed, there is illustrated in Figures 1 and 2, for purposes of disclosure, a machine for compacting material in containers, the supporting frame of which is very similar to those disclosed in the patents hereinbefore mentioned.

Briefly, the supporting frame comprises longitudinally extending frame members 2 and 3 supported upon suitable legs 4 adapted to rest upon a floor or suitable foundation, and preferably having a longitudinally extending tie member 5 connecting together the lower portions thereof. A horizontally disposed conveyor belt 6 is mounted on rollers 7 and 8 provided respectively at the receiving and discharge ends of the machine. The rollers 7 and 8 are so arranged that the upper run of the belt 6 is adapted to receive the filled bags as they are delivered to the machine from the left hand end thereof, when viewed as shown in Figures 1 and 2.

A fixed supporting plate 9 is interposed between the frame members 2 and 3 at the receiving end of the machine, as shown in Figure 1, and a relatively shorter belt supporting plate 11 is provided at the discharge end of the machine adjacent to the roller 8.

The lower run of the conveyor belt 6 is supported on idler rollers 12 and 13, and a belt adjusting pulley 14 may be provided at the receiving end of the machine for tensioning the belt 6, as will be understood by reference to Figure 1. The belt may be driven by a suitable chain drive 15 connecting the shaft 16 of the pulley 8 with a suitable speed reducer, generally indicated by the numeral 17.

The speed reducer 17 is driven through a suitable coupling 18 from a shaft 19 having its intermediate portion mounted in a suitable housing 21 and its opposite end provided with a coupling 22 connecting it to one end of a suitable shaft 23 having a crank 24 supported within a suitable housing 25, as shown in Figure 1. The shaft 23 is shown supported in suitable bearings 26 and 27, and may be driven from a motor 28 through a suitable drive 29.

A shaft 31 is connected to the opposite end of the shaft 23 and has a crank 24 mounted in the housing 25 similar to the shaft 23 provided adjacent the discharge end of the machine. A suitable coupling 32 connects the shaft 31 with the shaft 33 mounted in the housing 34, and the opposite end of which has a coupling 35 connecting it to a shaft 36 of a speed reducer 37

similar to the one shown at 17 at the opposite end of the machine.

The cranks 24 of the shafts 23 and 31, respectively, have connecting rods 38 connecting them to a horizontally disposed shaker frame, generally designated by the numeral 39, which has an upper longitudinally extending plate 41 providing a support for the intermediate portions of the upper run of the conveyor belt 6, as clearly illustrated in Figure 1. Secured to the bottom of the frame 39 are cylindrical portions 42 which are guidingly supported in suitable guides 43 provided in the housings 25. These guides guidingly support the frame 39 for limited movement in a vertical direction, when the cranks 24 are rotated, thereby to impart a vibratory action to the conveyor belt 6, as is well known.

The means for thus imparting a vibratory or shaking action to the conveyor belt 6 is shown and described in detail in the patents hereinbefore mentioned, and therefore need not be described in further detail in the present application.

An important feature of the present invention resides in the means provided in conjunction with the vibrating mechanism for causing the contents of the bags to settle more firmly therein, as the bags travel through the machine.

The means provided for thus causing the material to become more firmly settled in the bags is shown comprising a pair of side belts 44 and 45, mounted upon suitable rollers 46 and 47, provided at the receiving and discharge ends respectively of the machine. Suitable means such as indicated at 48 in Figures 1 and 2, is provided for tensioning the side belts 44 and 45, as will be understood.

The rollers 46 provide the drive means for the side belts and may be driven from a cross shaft 49 having driving connections with the rollers through suitable gears 51. The shaft 49 is shown provided with a sprocket 52 having a chain 53 which is driven from the speed reducer 37, shown in Figures 1 and 6.

Means is provided for causing the belts to impart a patting action to the bag bodies as they are moved through the machine, and is shown comprising opposed backing plates or members 61 arranged to engage the outer surfaces of the inner runs 62 of the side belts, as best shown in Figures 2 and 5. The backing plates 61 are adjustably mounted upon a pair of longitudinally extending rails 63 by suitable brackets 64, shown in Figures 2, 3 and 5, whereby the spacing therebetween may be varied in accordance with the size of bags to be passed through the machine. Bolts 50 are receivable in slots 60 in the brackets 64 for effecting such lateral adjustment of the backing plates 61.

To cause the backing plates to impart a patting action to the side belts 62, means is provided for imparting a horizontal rotary motion to the backing plates, as diagrammatically illustrated in Figure 7. The means provided for thus imparting a limited horizontal movement to the backing plates 61 is shown comprising suitable eccentrics 66 mounted on the upper ends of upright shafts 67 shown supported in bearings 68 and 69. The lower ends of the shafts 67 adjacent the receiving end of the machine, are shown driven from the shaft 33 by a worm gear drive, generally designated by the numeral 71, having suitable trains or gears 72 and 73 connecting it with the shafts 67.

The cross shaft 49 and the upright shafts 54

of the rollers 46 are mounted in suitable brackets 55 which in turn are adjustably secured to a supporting plate 56 by suitable bolts or screws 57, movable in slots 58 in the plate 56, whereby the spacing *s* between the rollers 46 may be varied to adapt the machine for handling bag bodies of various sizes. Similar means is provided at the discharge end of the machine for varying the spacing between the rollers 47, transversely of the machine.

One of the important features of the present invention resides in the construction of the side belts 44 and 45. These belts, as clearly illustrated in Figures 1-4, inclusive, are provided with vertically disposed cleats or indenting elements 59 which are spaced apart lengthwise of the side belts, as best shown in Figures 2 and 3. The inner or adjacent runs 62 of the side belts, it will be noted by reference to Figures 2 and 3, are preferably disposed in parallel relation to the conveyer belt 6, whereby they will engage opposite sides of the bag bodies with substantially uniform pressure the length of the side belts. In some cases it may be found more desirable or effective to so position the backing plates that the lateral pressure exerted against the bag bodies by the side belts may be relatively greater at one end of the machine than at the other. This may readily be accomplished by manipulation of the bolts 50 and 51, as will be understood by reference to Figures 5 and 6.

A similar oscillatory movement is imparted to the backing plates at the discharge end of the machine by similar eccentrics 66 driven in a manner similar to that shown in Figure 5, but from the shaft 19 shown supported in the housing 21 at the discharge end of the machine.

The outer runs of the side belts are shown guidingly supported by vertically spaced longitudinally extending upper and lower guides 74 and 75, best shown in Figure 5. The lower guides 75 are shown secured to longitudinally extending angle bars 76, which in turn are secured to the lower ends of upright supporting brackets 77, shown in Figure 5. The upper guides 74 are similarly secured to the brackets 77 by angle brackets 78. Vertically disposed rollers 70 are provided at the ends of the guide members 74 and 75 at each side of the machine, as indicated in dotted lines in Figure 2, to guide the belt runs into and out of the guides 74 and 75.

Suitable guides 79 may be provided at the receiving end of the machine to facilitate guiding the filled bags onto the conveyer belt 6.

Operation

In the operation of the novel machine herein disclosed, the filled bags are delivered onto the conveyer belt 6 at the receiving end of the machine, and, as they are advanced thereby, the inner runs 62 of the side belts will engage and impart to the opposite walls of the bag bodies a patting action, as a result of the oscillatory or horizontal movement of the backing plates 61. Simultaneously, as the side belts continue to tap or pat the side belts, a shaking action in a vertical direction is imparted to the bag bodies, as a result of the vibratory action imparted to the plate 41 by the cranks 24.

The spacing between the side belts is such that when the backing plates 61 are in their outermost positions, as shown in full lines in Figure 3, and dotted lines in Figure 7, the cleats 59 of the side belts may only slightly touch the walls of the bag bodies. When the backing plates 61

are in their innermost positions, as shown for example in Figure 2, the side belts slightly compress the bag bodies therebetween and simultaneously the cleats indent portions of the walls of the bag bodies to displace portions of their contents and form fissures therein, which action, in combination with the vibratory action imparted to the bag bodies, will permit air entrained with the flour or contents to readily escape therefrom without "spouting" of the contents, and whereby the contents of the bags will more firmly settle into the bag bodies. This action is repeated in rapid succession as the bags advance through the machine so that by the time the bags reach the discharge end thereof, the contents of the bag bodies will have become firmly settled therein, whereby the bag tops may be closed and sealed with the assurance that the bag walls will not become loose from subsequent handling of the bags.

In addition to causing the contents of the bag bodies to become more firmly settled therein, the patting action imparted to the bag bodies as they are being vibrated by the conveyer belt 6, also serves to square or align the bags in the conveyer, whereby the axis of the bag bodies will be disposed in substantially right angular relation to the conveyer belt 6, which is important to assure that all bag bodies will be uniformly shaped.

The side belts 62 and conveyer belt 6 may be operated at the same traveling speed, if desired, or the conveyer belt 6 may be operated at a slightly faster traveling speed than the side belts, thereby to compensate for slippage between the conveyer belt 6 and the bottoms of the bags as a result of the vibratory action imparted to the bags which, it will be understood, causes the belt 6 to actually move out of contact with the bottoms of the bags on the downward movement of the vibrating plate 41.

The combined patting and vibratory actions imparted to the bag bodies may be compared with the manual method of settling the contents of a bag by frequently dropping the bag in an upright position upon a table top and at the same time patting the side walls thereof with the hands.

Suitable means, not shown, may be provided for varying the speed of the side belts relative to the speed of the conveyer belt, if desired. From actual experience, however, I have found that for a given product, as for example flour, the conveyer belt 6 may be operated at a slightly higher traveling speed than the side belts. The side belts 62 may be so adjusted with respect to the sides of the bag bodies that they will actually control the feeding of the bags through the machine, due to the cleats 59 continually intermittently engaging and indenting the bag walls as a result of the patting action imparted to the side belts by the backing plates 61.

The present machine distinguishes from the structures disclosed in the above mentioned patents in that the means for engaging and intermittently indenting the walls of the bag bodies travels with the bags. The action imparted by the belt runs 62, in combination with the vibratory action imparted to the conveyer belt 6, is such that finely comminuted or pulverized materials, such as flour, and many other products, may be readily compacted in the bags without danger of the material "spouting" from the bags as a result of air which may be entrained therewith and which is forced out when applying pressure against the bag walls.

The cleats 59 and backing plates 61 are so arranged with respect to the bag bodies that the pressure imparted to the bag bodies is not sufficient to cause spouting of the flour from the bags, but just enough to constantly agitate or displace portions of the flour or contents of the bag bodies, as the latter travel through the machine, that by the time the bags reach the discharge end of the machine, the flour will have become very firmly compacted therein. When the material has thus been firmly compacted in the bags, the open tops thereof may be closed and sealed in the usual manner with the assurance that every bag body will be uniform in size and shape.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

What I claim is:

1. In a machine of the class described, a conveyor belt for advancing filled bags through the machine, opposed side belts, vertically disposed cleats on the side belts adapted to engage the bag bodies, and means engageable with the outer surfaces of the side belts for periodically moving said side belts inwardly to impart a patting action to opposite sides of the bag bodies and to

cause said cleats to intermittently indent the walls of the bag bodies to partially displace portions of the contents thereof whereby the contents of the bag bodies will become more firmly settled therein.

2. In a machine of the class described, a horizontal conveyor belt or advancing filled bags through the machine, side belts for the conveyor having vertically disposed cleats thereon spaced apart lengthwise of the belt and adapted to engage opposite sides of the bag bodies, means for moving said belts at similar speeds, means for imparting a vibratory action to the conveyor belt in a vertical direction, backing plate members engageable with the outer surfaces of the side belts, and means for periodically imparting a limited lateral motion to said plate members whereby they will simultaneously impart patting actions to the side belts and, in turn, impart a similar patting action by the side belts to opposite sides of the bag bodies, thereby to cause the cleats on the side belts to intermittently indent the bag walls in rapid succession, whereby the contents of the bags will become more firmly settled therein.

HAROLD V. KINDSETH.
